(57) **CLAIM**

The ornamental design for a frog-shaped fishing lure, as shown and described.

DESCRIPTION

FIG. 1 is a perspective view of a frog-shaped fishing lure showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view thereof;

FIG. 7 is a rear elevational view thereof;

FIG. 8 is a perspective view of a second embodiment of a frog-shaped fishing lure showing my new design;

FIG. 9 is a right side elevational view thereof;

FIG. 10 is a left side elevational view thereof;

FIG. 11 is a top plan view thereof;

FIG. 12 is a bottom plan view thereof;

FIG. 13 is a front elevational view thereof; and,

FIG. 14 is a rear elevational view thereof.

The portions shown in broken lines form no part of the claimed design.
